UNITED STATES PATENT OFFICE.

ARNOLD F. SINCLAIR, OF NEW YORK, N. Y.

DRIER.

1,294,547.

Specification of Letters Patent. Patented Feb. 18, 1919.

Application filed September 16, 1916. Serial No. 120,433.

To all whom it may concern:

Be it known that I, ARNOLD F. SINCLAIR, a citizen of the United States, residing at New York city, in the county of New York 5 and State of New York, have invented certain new and useful Improvements in Driers, of which the following is a specification.

My invention relates to machines for drying pulverized substances, and particularly 10 those substances which will be destroyed or injured if brought in contact with a flame. The machine which I have invented is of a special value in drying pulverized coal to be used as fuel in cement kilns, but is applicable also to the drying of many other 15 substances.

In machines heretofore used for the drying of pulverized coal, it has been customary to leave a space or opening between the 20 furnace and the body of the drier in which the pulverized coal is contained. This space was necessary in former machines to prevent the flame from the furnace entering the drier and igniting and destroying the 25 pulverized coal. In these machines, therefore, it was impossible to conduct the hot gases from the furnace directly through the body of the drier containing the pulverized coal. In consequence, much of the heat in these 30 gases was wasted.

I have invented a drier in which the hot gases from the furnace are passed directly through the cylinder containing the material to be dried. The body of my drier is connected directly to the furnace, but a screen 35 or series of screens is interposed at the outer end adjacent to the furnace, whereby the flames in the furnace are prevented from entering the body of the drier. By this 40 means I obtain efficient heating of the drier without danger of igniting the pulverized material.

One embodiment of my invention is illustrated in the accompanying drawings, in 45 which—

Figure 1 is a side elevation of my drier partly in section;

Fig. 2 is a transverse section taken on the line 2—2 of Fig. 1;

Fig. 3 is a similar section taken on the line 3—3 of Fig. 1;

Fig. 4 is a similar section taken on the line 4—4 of Fig. 1; and

Fig. 5 is an enlarged sectional elevation 55 of the end of my drier adjacent to the furnace.

Fig. 6 is a diagrammatic illustration of a portion of the flame arresting screen, indicating different degrees of mesh.

In the drawings, 1 represents the furnace and 60 2 the chimney through which the products of combustion from the furnace escape into the outer air. Between the furnace and the chimney is a rotary cylinder 3. This cylinder is supported on the roller bearings 65 4, 4, and rotated by power applied to the gear 5. The left-hand end of the cylinder 3 has a close running fit with the wall of the furnace, while the right-hand end has a similar fit with the lower portion of the 70 chimney. Within the cylinder are the shelves or Z-bars 6, which gather up and scatter the pulverized material when the cylinder is rotated, the rotation being in a clockwise direction (Fig. 4).

A chute 7 is placed in the lower portion 75 of the chimney 2 for feeding the pulverized material into the right-hand end of the cylinder.

Near the left-hand end of the cylinder are 80 a series of screens 8. The object of these screens is to prevent the flame from entering the cylinder, while at the same time permitting the hot products of combustion to pass through it. A single screen may be 85 used for this purpose, but I have found that if only one screen is used, it is necessary to make the mesh of the screen very fine, in order to prevent the admission of the flame. A single fine screen, while operating satisfactorily at first, will not long endure the 90 heat which is brought in contact with it. In order to provide means for excluding the flame which will successfully endure the great heat at the furnace end of the drier, I 95 find it preferable to provide a series of six screens spaced about two inches apart. The screens are of different mesh, the outer screen, that is the screen nearest the furnace, being the coarsest and that farthest from the furnace being the finest. I have found it satisfactory to make the first screen eight mesh, the second ten mesh, the third twelve mesh, the fourth fourteen mesh, the fifth eighteen mesh, and the last twenty mesh.

I preferably use a flange 9 at the left-hand end of the cylinder 3 to direct the hot gases toward the central part of the cylinder.

The presence of the screen at the left-hand end of the cylinder in my drier prevents the removal of the pulverized material from the end of the cylinder, as has been

customary in previous driers. I have, therefore, provided means for removing material through the wall of the cylinder. These means consist of a series of openings 5 10, just to the right of the screen 8. The portion of the cylinder containing these openings is surrounded by an annular casing 11. This casing has a running fit with the cylinder, but does not rotate with it. 10 It is held against rotation by a bracket or brace arm 13 anchored in the wall of the furnace and attached by a bolt or otherwise to the casing, or by any other suitable means within the skill of the mechanic. At 15 the bottom of the casing 11 is a discharge chute 12. The cylinder 3 is slightly inclined from right to left, so that the material introduced at its right-hand end will work toward the left-hand end and be discharged through the apertures 10 and the chute 12.

I wish it clearly understood that my invention is not limited to the precise apparatus described.

25 What I claim is:—

1. A drier comprising a furnace, a drying chamber connected to said furnace and from which ignition flame is excluded, and a flame arresting screen between said furnace 30 and said drying chamber.

2. A drier comprising a furnace, a drying chamber connected to said furnace so that the products of combustion from said furnace pass through it and from which ignition flame is excluded, and a flame arresting screen between said furnace and said drying chamber. 35

3. A drier comprising a furnace, a chimney, a drying chamber between said furnace 40 and said chimney through which the products of combustion from said furnace pass and from which ignition flame is excluded, and a flame arresting screen between said furnace and said drying chamber.

4. A drier comprising a furnace, a rotary drying chamber connected to said furnace and from which ignition flame is excluded, and a flame arresting screen at the end of said drying chamber adjacent to said furnace. 45

5. A drier comprising a furnace having a wall containing a circular aperture, a cylindrical drying chamber having a running fit with said aperture in the wall of said furnace and from which ignition flame is excluded, a flame arresting screen at the end of said drier adjacent to said furnace, and means for rotating said drying chamber. 50 55

6. A drier comprising a furnace, a drying chamber connected to said furnace and from which ignition flame is excluded, and a series of flame arresting screens between said furnace and said drying chamber. 60

7. A drier comprising a furnace having a wall containing a circular aperture, a chimney spaced apart from said furnace having a wall containing a circular aperture, a rotary drying cylinder having a running contact with the circular aperture in said furnace wall at one of its ends and a running contact with the circular aperture in said chimney with the other of its ends and from which chamber ignition flame is excluded, and a flame arresting screen in said cylinder near the end adjacent to said furnace. 65 70 75

8. A drier comprising a furnace having a wall containing a circular aperture, a chimney spaced apart from said furnace having a wall containing a circular aperture, a rotary drying cylinder having a running contact with the circular aperture in said furnace wall at one of its ends and a running contact with the circular aperture in said chimney with the other of its ends and from which chamber ignition flame is excluded, a flame arresting screen in said cylinder near the end adjacent to said furnace, means for introducing pulverized material at one end of said cylinder, means for discharging pulverized material near the other end of said cylinder and comprising an aperture in the wall of said cylinder, a fixed annular casing surrounding said cylinder and inclosing said aperture, and a discharge opening in said annular casing. 80 85 90 95

9. A drier comprising a furnace, a drying chamber connected to said furnace, and from which ignition flame is excluded, and a series of spaced flame arresting screens between said furnace and said drying chamber. 100

10. A drier comprising a furnace, a drying chamber connected to said furnace, a series of screens of different mesh between said furnace and said drying chamber, the screen nearest the furnace being of the coarsest mesh, and that farthest from the furnace being of the finest mesh. 105

11. A drier comprising a furnace, a drying chamber connected to said furnace, and a series of spaced screens of graded mesh between said furnace and said drying chamber, the screen nearest the furnace being the coarsest and that farthest from the furnace the finest. 110

ARNOLD F. SINCLAIR.
